CALUTRON

Ernest O. Lawrence and William M. Brobeck, Berkeley, Calif., assignors to the United States of America as represented by the United States Atomic Energy Commission

Application August 15, 1946, Serial No. 690,802

9 Claims. (Cl. 250—41.9)

This invention relates to electromagnetic devices for moving mechanical elements back and forth between predetermined positions, and the invention is illustrated herein as applied to a device, known as a "calutron," for separating isotopes on a scale yielding commercially useful quantities of the separated material. For a complete disclosure of a calutron and its mode of operation, reference is made to the copending application of Ernest O. Lawrence, Serial No. 557,784, filed October 9, 1944, for "Methods and Apparatus for Separating Materials" now Patent No. 2,709,222.

As disclosed in the above-mentioned Lawrence application, a presently preferred form of the calutron comprises an evacuated tank disposed between the poles of an electromagnet so that the evacuated space within the tank is pervaded with a substantially uniform magnetic field of high flux density. Within the tank, there is provided a "source unit" adapted to project a beam of positive ions of a polyisotopic charge material along an arcuate path extending transversely through the magnetic field, whereby the paths of ions of different mass are caused to diverge toward respective foci disposed 180° along the arcuate beam path from the source unit. A "receiver," also disposed within the tank, is positioned at the 180° foci of the streams of ions of different isotopes for separately collecting the component particles of one or more of those streams.

The receiver of the calutron comprises a viewing face disposed in the path of the beam for defining a separate beam delimiting slot for each ion stream from which the collection of material is desired, each such slot being adapted to pass a delimited portion of the beam enriched with respect to a particular isotope component; and a separate ion collecting pocket is disposed behind each such slot for receiving and retaining the particles passing therethrough. During focusing of a calutron ion beam on the viewing face of a receiver, it is desirable to close the beam delimiting slot or slots therein against the admission of ions until the focusing operation has been completed in order to avoid contaminating the pocket or pockets with material that is desired to exclude therefrom. For this purpose, a suitable door is generally mounted on the receiver for movement between open and closed positions with respect to the beam delimiting slot or slots, and a suitable mechanism controllable from outside the calutron tank is provided for opening and closing the door. Where such mechanism is entirely a mechanical one, it is necessary for some type of movable rod or the like to be passed from the receiver door through a wall of the tank to the exterior where it can be appropriately manipulated. This requires the employment of some form of air seal where the rod passes through the wall of the tank in order to prevent leakage of air into the tank. A similar problem is encountered whenever a mechanical element disposed inside a calutron tank must be moved during operation of the calutron.

Accordingly, it is an object of the invention to provide in the calutron tank a mechanism adapted to cooperate

with the calutron magnetic field pervading the interior of the tank for moving a mechanical element also disposed inside the tank without employing a movable element passing through a wall thereof.

5 A more specific object of the invention is to provide a mechanism disposed within a calutron tank and adapted to make an auxiliary electrodynamic or electromagnetic use of that magnetic field for opening and closing a door associated with an ion receiver, also disposed within the tank.

10 Still other objects and advantages of the invention will become apparent from the following disclosure of a preferred embodiment thereof, taken in conjunction with the accompanying drawing, in which:

Fig. 1 is a schematic plan view of a calutron including a tank, a source unit disposed within the tank for projecting an ion beam along an arcuate path, and a receiver unit disposed within the tank in the path of the ion beam, the receiver being provided, in accordance with the invention, with an electromagnetically controlled mechanism for moving a door associated with the receiver;

Fig. 2 is a vertical sectional view through the calutron shown schematically in Fig. 1, the view being taken as indicated by the line 2—2 in Fig. 1 for showing in greater detail the receiver, the receiver door, and the mechanism for moving the door; and

Fig. 3 is an elevational view of the receiver, the receiver door, and the mechanism for moving the receiver door, the view being taken as indicated by the arrow 3 in Fig. 2 with a portion of the mechanism for moving the door shown in section.

Referring to the structure shown in the drawings, a calutron tank 11, having a suitable pump-out conduit 12 for evacuating the tank, is disposed between a pair of vertically spaced-apart pole pieces 13 of an electromagnet adapted to create a magnetic field pervading the interior of the tank and passing upwardly therethrough, as indicated by lines 14 in Fig. 2. As shown schematically in Fig. 1, a source unit 16 is disposed within the tank 11 for projecting an ion beam 17 along an arcuate path within the tank, the path extending transversely to the magnetic field toward a receiver 18. The receiver 18 is mounted within the tank 11 on a supporting tube 19.

As shown in Figs. 2 and 3, the receiver 18 comprises a frame 21 carried by the supporting tube 19 and a simple box-type of ion collector 22 having a beam delimiting slot 23 in one wall thereof for admitting into the collector a selected portion of the ion beam. In order to avoid contaminating the interior of the collector 22 during initial focusing of the beam and before beam conditions have been obtained that are suitable for collection purposes, a door or shield 24, that may merely consist of a flat strip of metal, is mounted for movement between an operative position (Fig. 3) in front of the slot 23, in which position the slot is closed to the passage of ions therethrough, and an inoperative position to one side of the slot 23 (shown in phantom outline in Fig. 3). The door 24 is mounted to permit such movement by means of a parallel motion linkage comprising two links 26 and 27 and a bracket 28. The bracket 28 is secured to the frame 21 at its upper and lower ends by suitable fastening elements 29. The link 26 is pivotally secured at one end to the lower end of the door 24 and at its opposite end to the lower end of the bracket 28; and the link 27 is pivotally secured at one end to the upper end of the door 24 and intermediate its ends to the upper end of the bracket 28. Adjacent the point where the link 27 is pivotally secured to the bracket 28, this link is provided with an angularly disposed extension 31 that projects a short distance to one side of the receiver 18 and supports a housing 32, preferably made of stainless steel and adapted to shield from ion bombardment a suitable electric motor

3

armature and winding for actuating the parallel motion linkage described above.

The structure comprising the armature and winding enclosed by the housing 32 includes a cylindrical core member 33 of any suitable material disposed between a pair of disks 34 of stainless steel or other suitably rigid material of low magnetic permeability. The disks 34 are larger in diameter than the core member 33 and define an annular space lined with suitable electrically insulating material 36 and adapted to receive the windings of a solenoid 37. The core and solenoid assembly is supported in the housing 32 by a bolt 38 that passes through the core member 33 and out of the housing through a collar 39 formed integrally with the housing. A tubular insulator 41, having a flanged end disposed inside the housing, and an insulating collar 42 disposed outside the housing encircle the bolt 38 and cooperate to hold the core and solenoid assembly rigidly in the housing and electrically insulated therefrom.

One electrical lead 43 of the solenoid 37 is grounded to the housing 32, and the other lead (not shown) is connected inside the housing to the bolt 38. A continuation 44 of the latter lead is run from the bolt 38 through a wall of the tank in any desired manner (not shown) to a suitable source of power operative to apply an electrical potential between the lead 44 and ground for energizing the solenoid.

By virtue of the fact that the core and solenoid assembly are disposed in the calutron magnetic field, energization of the coil by passing a current therethrough in the proper direction will, according to well known principles, cause the assembly to move from its lowermost position (shown in Figs. 2 and 3) to its uppermost position (shown in phantom outline in Fig. 3). When the core and solenoid assembly moves upwardly in response to energization of the solenoid 37, the parallel motion linkage is actuated to move the door 24 to its inoperative position to one side of the beam delimiting slot 23, and the door is held in its inoperative position as long as current is flowing through the solenoid. When the flow of current through the solenoid is interrupted, the weight of the core and solenoid assembly is sufficient for it to drop downwardly to its lowermost position under the influence of gravity, thereby moving the door 24 back to its operative position in front of the beam delimiting slot 23.

From the foregoing, it will be appreciated that a mechanism has been provided for actuating the door of a calutron receiver that is extremely simple in its construction and operation and that does not require passing a mechanically movable element through a wall of the tank. While a specific embodiment of the invention has been disclosed herein in detail, it will also be appreciated that these details are subject to considerable modification without departing from the true spirit and scope of the invention as defined in the appended claims.

What is claimed is:

1. In a calutron including a tank adapted to be evacuated, means for creating a magnetic field within said tank, and means for projecting an ion beam within said tank

5 along a path determined by said magnetic field; an adjustable element mounted within said tank, and means including an electrically conducting coil disposed within said tank and reacting with said magnetic field for moving said adjustable element.

2. In a calutron including a tank adapted to be evacuated, means for creating a magnetic field within said tank, and means for projecting an ion beam within said tank along a path determined by said magnetic field; an adjustable element mounted within said tank, and means including an electric current carrying conductor disposed within said tank and cooperating with said magnetic field for moving said adjustable element.

3. In a calutron including a tank adapted to be evacuated, means for creating a magnetic field within said tank, and means for projecting an ion beam within said tank along a path determined by said magnetic field; an adjustable element mounted within said tank, and means including an armature provided with a current carrying winding and disposed within said tank and cooperating with said magnetic field for moving said adjustable element.

4. In a calutron including a tank adapted to be evacuated, means for creating a magnetic field within said tank, and means for projecting an ion beam within said tank along a path determined by said magnetic field toward an ion receiver disposed in the path of said beam for receiving ions traveling therein; a door mounted on said receiver for movement between operative and inoperative positions, and means including an electrically conducting coil disposed within said tank and reacting with said magnetic field for moving said door from one of said positions to the other.

5. In a calutron having an evacuated tank pervaded with a magnetic field, means for projecting an ion beam within said tank along a path determined by said field, a stationary ion receiver disposed in said tank, a movable shield adapted to prevent the impingement of said ion beam upon said receiver, an electrical conductor movably mounted within said tank and adapted to utilize said magnetic field during its movement, means connecting said movable conductor to said shield, and means for supplying electrical current to said conductor.

6. Apparatus as defined in claim 5 wherein said conductor comprises a motor armature and winding enclosed within a housing of low magnetic permeability.

7. Apparatus as defined in claim 5 wherein said means connecting the conductor and shield comprises a mechanical linkage.

8. Apparatus as defined in claim 5 wherein said shield is normally held in shielding position by gravity.

9. Apparatus as defined in claim 5 wherein said movable conductor is disposed laterally of said ion receiver.
